No. 874,783.

PATENTED DEC. 24, 1907.

J. MATHY.

GRATE FOR METALLIC CRATES.

APPLICATION FILED APR. 11, 1907.

UNITED STATES PATENT OFFICE.

JOSEPH MATHY, OF HOT SPRINGS, ARKANSAS.

GRATE FOR METALLIC CRATES.

No. 874,783.

Specification of Letters Patent.

Patented Dec. 24, 1907.

Application filed April 11, 1907. Serial No. 367,570.

To all whom it may concern:

Be it known that I, JOSEPH MATHY, of Hot Springs, in the county of Garland and State of Arkansas, have invented certain new and useful Improvements in Grates for Metallic Crates; and I hereby declare that the following is a full, clear, and exact description thereof, reference being had to the accompanying drawings, which form part of 10 this specification.

This invention is an improvement in grates for metallic crates such as are used for transporting bottled beer, milk, cream, etc., and particularly designed for use in connection with metallic crates such as are shown in my Patent No. 678,826 dated July 16, 1901, and the object of the present invention is to provide a simple, strong and cheaply constructed grate, which is preferably removable and can be readily placed in or removed from the crates, and when in position will properly separate the bottles in the crate.

Some of the particularly novel features of the grate are the means by which it is supported within the crate and the peculiar locking joint between the supports and the crate proper, whereby the supports also serve as a bond to tie the members of the grate together.

The invention will be clearly understood from the following description, in connection with the accompanying drawings, and the claims set forth the construction for which protection is desired.

In said drawings—Figure 1 is a view of a crate, the crate broken away so as to show the grate in position therein, and showing the grate cover; Fig. 2 is a detail sectional view showing the crate cover; Fig. 3 is a perspective view of the grate removed from the crate. Figs. 4 and 5 are plan views of slight modifications of the grate. Fig. 6 is a perspective view of one of the locking joints between the support and grate straps. Fig. 7 is a perspective view of such joint opened; and Fig. 8 is a perspective view showing the device for locking the grate straps at an intersecting point.

The crate A is preferably made of sheet metal having its side and end walls slightly tapered inward from top to bottom, so that its upper end is smaller than the bottom flange thereof, so that one crate can be placed on top of another and "nested", the flange A' on the lower edge of one crate fitting over the upper end of a lower crate. In

order to exclude air from the crate, and to protect the contents thereof from injury when the crate is transported singly, I provide it with a cover B. This cover is preferably stamped out of sheet metal, and has a depending flange b adapted to fit closely around the upper edge of the crate A, said upper edge being ordinarily stiffened by a metal band a. This cover forms a kind of cap, the flange b depending on the sides and ends of the crate sufficiently to not interfere with the placing of one crate upon another, as indicated in Fig. 2. Preferably the lower edge of flange b is stiffened by a wire b', as shown, and at one side this cover is hinged to the crate by means of strap metal loops C engaging the wire b' at points where the encircling portion of the flange is cut away, as indicated at b³. At the opposite side the cover can be fastened by means of a sheet metal hasp D strung on wire b', and provided with a slot adapted to engage a fastener d pivotally attached to the adjacent wall of the crate.

The grate is composed of a series of longitudinal parallel bars or straps 1 and a series of intersecting transversely arranged straps 2. The straps 1 are provided at intersecting points with notches 1^a on their upper sides and the straps 2 are provided with notches 2^a on their underside, so that when the notch portions of the straps are fitted together at their points of intersection, the edges of the straps will be substantially flush, as indicated in the drawings, and all the straps will be practically in one plane.

The grate is held at a proper height by means of supports 3, preferably U-shaped bails—which are provided with slots 3^a in their upper ends by which they are adapted to embrace a strap 2 at a point of its intersection with a strap 1. The strap 2 rests upon the bottom of the slot 3^a; and the projecting extremities 3^b of the support are turned over the upper edge of the strap 1 and bent down against the opposite side of such strap, as indicated in Fig. 6 of the drawings, thus forming a perfect lock preventing the straps 1 and 2 separating vertically, and as said straps are locked against longitudinal relative movement by the notches 1^a, 2^a, the resultant joint forms an absolutely tight connection between the support and both straps without the use of any rivets or sockets. Thus the grate proper is supported at the proper height within the crate, the supports

are out of the way of the bottles, and the construction is simple, compact and effective.

- If desired, in large grates, as indicated in Figs. 1 and 3, the straps may be inclosed 5 within a band 4, to which the outer ends of the several straps 1, 2, may be riveted as at 1^e, 2^e, which makes a very substantial grate. But as indicated in Fig. 5, this band 4 may be omitted, making a lighter grate. Where the 10 band 4 is omitted the ends of the straps 1, 2, may be rounded, as indicated at 1^d, 2^d, in Fig. 8, so that they will not be likely to injure the hand of the operator in placing or removing the grate in the crate.
- 15 In order to prevent the straps 1, 2, swinging apart at intermediate intersections where they are not locked by the supports or by rivets, they may be secured by a locking device 5, as indicated in the drawings. This 20 locking device may comprise an open wire loop, which is slipped under the strap 2 at a point of intersection with strap 1, the upper ends of the device are then bent down over the adjacent interlocked strap 1, as indicated 25 in Fig. 8 of the drawings, forming substantially the same positive lock between said straps as is formed by the slotted upper end of the support 3, as shown in Fig. 6. In fact, the wire is simply a similar but equivalent 30 construction of the slotted upper end of one of the supports 3. It is not necessary to use these locking devices 3 or 5 at every point of intersection of the straps 1, 2.

The grate shown and described is very 35 simple in construction, strong and durable, and as the supports uphold the grate some distance above the floor of the crate, the grate can be fitted closely in the crate and yet easily removed and replaced, because it 40 can be tilted in the crate to different angles before the supports 3 would contact with the walls of the crate.

Having described my invention what I 45 claim as new and desire to secure by Letters Patent is:—

1. The combination of a grate composed of intersecting straps, with supports attached to the grate at points of intersection of the straps and locking the straps together, substantially as described.

2. The combination of a grate composed of longitudinal and transversely arranged series of straps, with supports having slotted upper ends embracing one of the straps at points 55 of intersection, and their extremities turned over the intersecting straps to lock the same, substantially as described.

3. The combination of a grate composed of longitudinal and transversely arranged series 60 of bars notched at their points of intersection, with supports having slotted upper ends embracing one of the straps at intersecting points and having their extremities turned over the adjacent intersecting straps to lock 65 the same, substantially as described.

4. The combination of a grate composed of longitudinal and transversely arranged series of straps, with supports having slotted upper ends embracing one of the straps at points of intersection, and their extremities turned over the intersecting straps to lock the same, and bands surrounding the intersecting straps and attached to the ends thereof.

5. The combination in a grate, of a series 75 of parallel straps notched on their upper side, a series of intersecting transversely arranged straps notched on their under side, said straps being fitted together at their notched intersecting points, with a locking device embracing the edge of one of the straps at an intersecting point and having its extremities turned over and down upon the opposite edge of the intersecting strap to lock the straps together, substantially as described.

6. The herein described movable grate consisting of a series of longitudinally disposed straps notched in their upper sides and a series of transversely disposed straps notched on their under sides, said straps being fitted together at their points of intersection with U-shaped bails having slotted upper ends embracing the lower edge of one strap at the point of intersection and having their extremities turned down over the upper edge of the intersecting strap whereby the supports are rigidly secured to the grate and the intersecting straps locked together.

7. The combination of a grate composed of longitudinal and transversely arranged series 100 of bars notched at their points of intersection, with supports having slotted upper ends embracing one of the straps at intersecting points and having their extremities turned over the adjacent intersecting straps 105 to lock the same; with a band inclosing the said straps and connected to the extremities thereof, substantially as described.

8. The combination in a grate, of a series 110 of parallel straps notched on their upper side, a series of intersecting transversely arranged straps notched on their under side, said straps being fitted together at their notched intersecting points, with a locking device embracing one of the straps at an intersecting point and engaging one edge thereof and having its extremities turned over and down upon the opposite edge of the intersecting strap to lock the straps together; with a band inclosing the said straps and connected 115 to the extremities thereof, substantially as described.

In testimony that I claim the foregoing as my own, I affix my signature in presence of two witnesses.

JOSEPH MATHY.
